R. H. COLLINS.
TOOL STORING DEVICE FOR AUTOMOBILES.
APPLICATION FILED MAY 5, 1920.

1,434,350.

Patented Oct. 31, 1922.

UNITED STATES PATENT OFFICE.

RICHARD H. COLLINS, OF DETROIT, MICHIGAN, ASSIGNOR TO GENERAL MOTORS CORPORATION, OF DETROIT, MICHIGAN, A CORPORATION OF DELAWARE.

TOOL-STORING DEVICE FOR AUTOMOBILES.

Application filed May 5, 1920. Serial No. 379,108.

To all whom it may concern:

Be it known that I, RICHARD H. COLLINS, a citizen of the United States, and a resident of Detroit, county of Wayne, and State of Michigan, have invented certain new and useful Improvements in Tool-Storing Devices for Automobiles, of which the following is a full, clear, concise, and exact description, such as will enable others skilled in the art to which the invention relates to make and use the same, reference being made therein to the accompanying drawings, which form a part of this specification.

My invention relates to automobiles and similar self-propelled vehicles, and particularly to means for storing the tools commonly furnished with and used about such vehicle for making minor repairs in such a manner that the tools will be securely stored when not in use, while at the same time they are readily accessible if and when occasion for their use arises.

The principal object of my invention is to provide an improved storage compartment associated with a door of the vehicle, together with a tool holding envelope adapted to lie within said compartment when the tools are not in use; my invention being illustrated in the drawing and herein described as associated with a vertically swinging door which closes a compartment at the rear end of the body of the vehicle, although my invention may be applied to and used in connection with doors otherwise arranged relative to the vehicle body.

A further object of my invention is to provide improved tool storing means comprising a storage compartment secured to a door of the vehicle and within which compartment a separate envelope in which various tools are held may be secured in place in such a way as to be easily removable from said receptacle or compartment, so that the envelope as a whole may be readily removed from the compartment in which it is stored and taken to the side or front of the vehicle; thus rendering all the tools accessible in a convenient manner and providing a holding envelope in which all are stored when not in use, and at the same time made available for removal to and use at any place about the vehicle.

With the above and other objects of invention in view, my invention consists in

the improved storage compartment or receptacle and the removable tool holding envelope associated therewith for holding the tools illustrated in the accompanying drawings and hereinafter described and claimed; and in such variations and modifications thereof, within the scope of the concluding claims, as will be obvious to those skilled in the art to which my invention relates.

Referring now to the drawing wherein the preferred embodiment of my invention is illustrated:

Figure 1 is a view showing the rear end of a motor vehicle body in elevation with a door or cover which closes a compartment in the rear of the said body open, so as to illustrate the manner in which my invention is associated with a door of the vehicle body.

Figure 2 is a view showing the tool holding envelope of my tool holding device removed from the compartment within which it is stored, and opened to permit tools to be removed therefrom.

Figure 3 is a view showing the tool holding envelope partially closed, so as to illustrate the tongue or strap whereby the same may be secured in place within the receptacle or pocket provided for its reception.

Referring now to the drawing: The reference numeral 5 designates an automobile body having a rear compartment 6 provided with an opening through which access may be had thereto, and which opening is closed by a door 7 pivotally supported by hinges indicated by the reference numeral 8; the door being supported along its further edge, regarded from a position to the rear of the vehicle, so that the same swings upward and forward when access is to be had to the compartment or space in the rear end of the vehicle body. A suitable toggle brace 9 is provided for holding the door in its open position as is usual in such devices.

Secured to the inner side of the door 7 is a sheet metal plate the central portion 10 of which is offset, and the end portions 11 of which rest upon the inner surface of the door; whereby a receptacle or compartment carried by the door is provided, and within which a tool containing or storing envelope indicated as a whole by the reference numeral 12 in Figure 1 is stored when the tools are not in use.

The tool holding envelope is shown sep-

arate and by itself in Figures 2 and 3 and the same comprises a main base or tool supporting portion 13 to which a plurality of pockets 14 are secured, and within which 5 pockets various kinds of tools may be placed, as clearly shown in Figures 2 and 3 of the drawing. Said envelope also comprises two end flaps 15, 15 which may be folded over and made to lie on top of the 10 tools, and the inner ends of which may be fastened together by co-operating separable fastening members 16; while other flaps 17 are connected with and extend from the side portions of the said base portion 13 15 and which last mentioned flaps may also be folded over and made to overlie the tools and the flaps 15, the free edges of said flaps 17 being likewise provided with co-operating pairs of separable fastening members 20 18, 18 which may be made to engage with one another, to thereby detachably hold said free edges together and provide a complete enclosing envelope or casing for the tools.

Secured to the envelope 12 within which 25 the tools are contained, and preferably to one of the triangular flaps 15 thereof, is a tongue 19, which tongue projects from the top portion or edge of the envelope when the same is closed and fastened in the manner above pointed out; the free end of said tongue being provided with a separable fastening member which may be made to engage with a co-operating fastening member located upon the offset wall 10 of the receptacle or pocket within which the envelope 30 is placed, as indicated by the reference numeral 20 in Figure 1, to thereby hold the envelope as a whole in place within the receptacle provided for its reception upon the 35 inner surface of the door 7.

It will be appreciated that after the flaps of the envelope have been folded inward and made to overlie the tools and to overlie one another and the free edges of said flaps 40 properly secured together, as hereinbefore explained, the entire envelope may be placed within the receptacle or compartment provided for its reception upon the inner surface of the door; and held in place within 45 said compartment by the tongue 19 and the separable fastening means 20 above referred to, and readily removed from said compartment when the tools are to be used. The envelope within which the tools are contained will thus be held in a pocket provided for its reception and the said tools kept together and easily accessible in case they have to be used, the envelope with the tools within the same being removed 50 from the compartment in question and taken to the vicinity in which they are to be used if and when it becomes necessary to use the tools or any of them.

It will be appreciated that my invention

may be applied to a door other than an upwardly swinging door employed to close a compartment at the rear end of the vehicle body; that securing members of any kind or type may be provided for holding the free ends on triangular flaps 15, as well 65 also as the free edges of the flaps 17 together after folding the envelope, to thereby 70 secure the tools in place therein; and that means other than the tongue 19 may, if deemed preferable, be employed for holding the envelope as a whole, together with the tools within it, in place within the compartment provided for its reception upon the door.

Again it will be obvious that the opening 80 into the tool-envelope receiving compartment in the door may be directed toward a free edge other than that opposite the hinges.

Having thus described and explained my 85 invention, I claim and desire to secure by Letters Patent:

1. In combination in an automobile body, a rear compartment having an opening closed by a pivotally supported and upwardly swinging door; a sheet metal plate secured to the inner surface of said door and the central portion of which plate is offset, to thereby provide a receptacle or compartment open at the end thereof which is uppermost when the door is open; a tool containing envelope adapted to fit within said compartment and comprising a body portion or base having pockets to receive tools, and two pairs of oppositely located 90 flaps adapted to fold upon and overlie said tools and to overlie one another; a tongue secured to said envelope adjacent the end thereof which is uppermost when the same 95 is in place within said compartment; and co-operating fastening members, one carried by said tongue and the other located adjacent the upper end of said receptacle or compartment, and which fastening members may be made to engage one another 100 to thereby hold said envelope in place within said compartment.

2. In combination in an automobile body, a rear compartment having an opening closed by a pivotally supported and upwardly swinging door; a sheet metal receptacle or compartment secured to the inner side of said door and open at the end thereof which is uppermost when the door is open; a tool containing envelope adapted to 115 fit within said compartment and comprising a body portion having pockets to receive tools, and flaps adapted to fold upon and overlie said tools; a tongue carried by said envelope; and co-operating fastening members one carried by said tongue and the other located adjacent the upper end of said 120 receptacle or compartment, and which fas-

tening members may be made to engage one another to thereby hold said envelope in place within said compartment.

3. In combination in an automobile body, 5 a rear compartment having an opening closed by a pivotally supported and upwardly swinging door; a receptacle or compartment upon the inner side of said door and which compartment is open at the end 10 thereof which is uppermost when the door is open; a tool containing envelope adapted

to lie within said compartment and comprising a body portion or base having pockets to receive tools, and flaps adapted to fold and overlie said tools; and means for holding said envelope in place within said compartment, said means being of such a character that said envelope may be readily removed from said compartment. 15

In testimony whereof I affix my signature.

RICHARD H. COLLINS.
